UNITED STATES PATENT OFFICE.

IMMANUEL G. SPEIDEL, OF BUFFALO, NEW YORK.

TOOTHBRUSH HOLDER.

Application filed December 18, 1922. Serial No. 607,414.

To all whom it may concern:

Be it known that I, IMMANUEL G. SPEIDEL, a citizen of the United States, residing at Buffalo, in the county of Erie and State 5 of New York, have invented new and useful Improvements in Toothbrush Holders, of which the following is a specification.

This invention relates to a holder for tooth brushes, which is designed to enclose 10 the brush head of the same when not in use and render the brush sanitary and prevent the contraction of disease.

It is the purpose of this invention to provide a holder of this character which effectively 15 protects the brush head of a tooth brush while not in use and treats the same with an antiseptic, and which may be operated conveniently and be produced at low cost.

20 In the accompanying drawings: Figure 1 is a perspective view of a tooth brush holder embodying my invention. Figure 2 is a horizontal section of the same taken on line 2—2, Fig. 3. Figure 3 is a vertical section taken on line 3—3, Fig. 1. Figure 4 is a vertical section taken on line 4—4, Fig. 5. Figure 5 is a horizontal section taken on line 5—5, Fig. 3. Figure 6 is a fragmentary vertical section taken on line 6—6, Fig. 5. 25 Similar characters of reference indicate corresponding parts throughout the several views.

In the accompanying drawings is shewn 30 an embodiment of my invention suitable for holding four tooth brushes, but it is to be understood that the same may be organized for holding a greater or lesser number of brushes. Although the form of tooth brush adapted to be supported by my improved 35 tooth brush holder may be varied those, for example, shown in the drawings, consist of a brush head 10 having bristles 11 and a handle 12 connected with the brush head by a reduced neck 13.

40 The enclosing casing of the holder in the preferred form shown in the drawings, comprises a rear upright wall 14 which may be secured to the building wall 15 by screws 16 or otherwise, a horizontal top 17 and bottom 18 projecting forwardly from the upper and lower edges of the rear wall, and upright end walls 19 connecting opposite ends of the top, bottom and rear walls, the several parts being preferably constructed 45 of a single sheet of metal.

The bottom of this casing is provided with one or more slots extending rearwardly from the front edge of the same, four of such slots being shown, and each slot having a narrow, straight parallel sided front part 60 20 and a wide or enlarged rear part formed by a notch 21 extending laterally from one side of the rear part of said slot. The neck of a tooth brush is passed rearwardly into one of said slots until the same reaches the 65 enlarged rear part thereof where the head may rest by the shoulder on one side of its lower end on the upper side of the bottom adjacent to the notch 21 which forms part of a seat therefor.

70 Means are provided for closing that part of each bottom slot when a tooth brush is supported in the inner or rear part of the same which means also preferably aid in supporting the tooth brush. In the pre- 75 ferred construction, these means consist of a horizontally swinging shutter of sheet metal which has its rear part pivoted by a rivet 22 or the like to the bottom of the casing adjacent to that side of the slot op- 80 posite to the notch thereof, so that the front part or body 23 of this shutter can cover and uncover the front part of the slot. Adjacent to the pivot 22 the shutter is provided on that longitudinal edge thereof facing the 85 notch 21 with a recess or notch 24 forming a shifting arm 25 on the shutter in rear of said pivot which arm is adapted to swing across the enlarged rear part of the slot.

Preparatory to mounting a tooth brush 90 on the holder, the shutter is turned so that its front body part clears the front part of the adjacent slot and its rear arm extends across the rear part of the slot, as shown at the right of Fig. 2, and the left of Fig. 5. 95 Upon passing the neck of a tooth brush backwardly into the respective slot with the brush head up and the handle down, the neck will first move freely through the narrow front part of this slot and then enter 100 the wide rear part thereof while its brush head enters the chamber above the bottom of the casing and the handle passes along the underside of said bottom. As the neck 105 of the brush enters the wide rear part of the slot, the same engages the shifting arm and pushes the same rearwardly until the neck reaches the rear end of this slot, thereby causing the front part of the shutter to be 110 swung across the narrow front part of the

respective slot and close the same, thereby practically preventing the passage of dust through this slot into the interior of the casing. The shifting arm of the shutter is 5 swung rearwardly by the neck of the tooth brush until the latter engages the rear end of the respective slot at which time this arm clears the rear end of this slot and the bight of the notch 24 forms a seat upon 10 which the shoulder on the adjacent lower end of the brush head rests and thus forms a support therefor together with the edge portion of the notch 21 in the bottom. Upon moving the tooth brush forwardly, the front 15 or body part of the shutter will be automatically pushed to one side of the slot by the neck of the brush and shift the arm across the rear part of the slot preparatory to receiving the brush for supporting and 20 storing the same.

The interior of the casing in this instance is divided by an upright transverse partition into two compartments the bottom portion of each of which contains two brush receiving slots. The front side of each of these compartments is closed by a door 26 which in its normal position extends across the front end of this compartment and completely closes the same but which can be deflected upon passing a tooth brush either into or out of one of the slots in the respective part of the bottom. For this purpose each of these doors is mounted midway of its upright edges and between two slots 23 on a pintle or shaft 27 the upper and lower ends of which form trunnions which are journaled in bearings or openings formed in the front parts of the upper and lower walls of the casing. This door is yieldingly 30 held in a position in which the same closes the front end of the respective compartment by an arm 28 projecting rearwardly from the lower end of the door shaft and a spring 29 connecting the free end of this arm with 35 the adjacent part of the casing.

By this means either end of a door will be deflected either inwardly or outwardly upon passing a brush into or out of one of the compartments but after the brush has cleared the door the latter will be automatically returned to its closed position, so that dust is excluded from the compartment and the brush stored therein is maintained in the most sanitary condition.

In order to prevent the bristles of the brush from coming in contact with the door while putting the same into the compartment or removing the same therefrom the brush should be pressed with the back of the head against the outer side of the door for pushing the latter inwardly and admitting the head, and the brush should be removed from the compartment while the same is in this same position relatively to the door. During the outward movement

however of the brush its neck engages with a horizontal flange 35 which preferably projects inwardly from the lower edge of the door and which is greater in width than the length of the bristles of the brush, thus 70 opening the door without permitting the bristles to touch the door and maintaining the brush in a sanitary condition.

In addition to excluding dust, the interior of the casing is preferably supplied with an 75 antiseptic vapor for the purpose of destroying disease germs and thus further increasing the sanitary condition of the tooth brushes stored in the casing. For this purpose, the partition is made hollow so as to serve as a tank 30 in which a supply of liquid antiseptic may be stored which is introduced into this tank through an opening in the top which is normally closed by a lid 31 hinged to the top. The vapors may be conducted from this tank into the tooth brush compartments in any suitable manner for instance by conducting the same from the top of this tank downwardly through a conduit 32 arranged in the corners between 80 the partition and rear wall and thence into delivery conduits 33 arranged horizontally in the corners between the rear wall and the bottom part of each chamber, each of said delivery conduits being perforated, as 85 shown at 34, so as to permit the vapors to pass from the delivery conduits forwardly and upwardly through the compartments and envelop the bristle heads of the brushes therein and thoroughly disinfect the same.

This device is comparatively simple and inexpensive in construction, it is convenient to use and also neat in appearance and therefore forms a desirable adjunct to the toilet outfit of a household.

I claim as my invention:

1. A tooth brush holder having a compartment provided in its front side with a door opening and in its bottom with a brush receiving slot extending to the front end of the bottom, an upright vertically pivoted door for controlling said door opening, and spring means for yieldingly holding said door in a normal closed position in which the same extends across said door opening and which permits said door to be pushed inwardly from its closed position upon inserting a brush into said slot and to be pushed outwardly from its closed position upon removing a brush from said slot.

2. A tooth brush holder having a compartment provided with a brush receiving slot and a door opening at its front side, a door for covering and uncovering said door opening, means for yieldingly holding said door in its closed position comprising an upright shaft carrying said door and pivoted on said casing and provided with an arm, and a spring connecting said arm with said casing and operating to close said door.

3. A tooth brush holder having a compartment provided on its front side with a door opening and in its bottom with brush receiving slots, a door arranged across the opening of said compartment, an upright shaft secured to the door between opposite vertical edges thereof and journaled in the top and bottom of the compartment, an arm projecting rearwardly from one end of said shaft, and a spring connecting the arm with a wall of the compartment and operating to close said door. 10

IMMANUEL G. SPEIDEL.
